LOAD HANDLING APPARATUS

Henri Dudouit, Le Havre, France

Application August 21, 1935, Serial No. 37,256
In France May 24, 1935

5 Claims. (Cl. 9—23)

This invention relates to an apparatus for handling heavy weights, also applicable to life boats and which can be automatically disconnected when the load or a portion of the load comes in contact with the platform adapted to receive it.

The apparatus is essentially constituted by a beam on the ends of which can be hooked members pivoted on arms which can be journalled on a shoe member supporting the load. The said members or hooks are provided with weights causing them to rotate about their pivot pins as soon as the weight of the load is no longer exerted on the same, so as to move said pivot pins apart in order that they should no longer be opposite the ends of the beam, thus allowing said arms carrying them, to move down on to the shoe member and to release the load from its suspension device.

This apparatus is particularly applicable to life boats in which the disengagement of the suspension cables must take place simultaneously and positively when the life boat or one of its ends touches the water, in order that the passengers should be in safety and to avoid a dangerous inclination of the life boat. For that purpose, use is made of two apparatus, one arranged at the front, the other at the rear.

A safety device holds the disengaging apparatus stationary during handling or manipulation for avoiding any accidental working of the apparatus.

The hooks can be disengaged by hand or automatically when the life boat comes in contact with the water, these hooks being connected together by a suitable connection.

The accompanying drawings illustrate, by way of example only, a form of carrying the invention into practice.

Fig. 1 is a perspective view of a handling apparatus.

Figs. 2 and 3 are an elevation and a plan view, respectively, showing a horizontal apparatus for automatically disengaging apparatus for handling life boats.

Figs. 4 and 5 are an elevation and a plan view, respectively, showing a vertical disengaging apparatus.

Figs. 6, 7 and 8 show the various phases of operation of the apparatus.

The handling apparatus, according to the invention, is constituted by a beam 1, terminating at each end in a shoulder 2. This beam 1 can be provided with a yoke 3, pivoted about a pivot pin 4, and attached to the end of a suspension cable 5a by any suitable means.

The shoulders 2 are engaged by members or hooks 5, pivoted about pivot pins 6 and provided with weights 7 causing them to rock for releasing the shoulders 2 when a vertical pull is not exerted on the same. The pivot pins 6 are arranged in the ends of arms 8 which are pivoted, through pivot pins 9, on a shoe member 10 which can be secured on the deck 11 of a life boat by lugs 12.

The handling device applied to a life boat is composed of two similar apparatus, one being secured at the front, the other at the rear, and capable of being adapted to the usual suspension system.

Small safety bars 13, pivoted on one of the arms 8, are engaged, through their ends 14 over pins 15 rigid with the opposite arm. These safety bars 13 are adapted to hold the members stationary during manipulation for preventing any accidental operation of the disengaging system.

When the safety bars 13 are disengaged, the apparatus operates automatically when the life boat touches the water in calm weather, owing to overcoming the vertical action of gravity which exerts itself on the arms 8 through the medium of the shoe member 10 for holding the hooks 5 over the shoulders 2 of the beam.

When, owing to the flotation of the life boat, the action of gravity on hooks 5 is overcome, the weights 7 becoming preponderant cause them to rock about the pivot pins 6 and, consequently, the arms 8 can rotate about the pivot pins 9, thus releasing the beam 1.

The rocking movement of the arms 8 is facilitated by the action of pins 16, carried by the beam and acting on their upper face owing to the hauling down of the suspension cables.

In rough weather, both apparatus of the system described above could not operate simultaneously, as one of the ends of the life boat might be lifted by a wave, causing the disengaging system to operate at the lifted end, which would give a dangerous inclination to the life boat and might be unsafe for the occupants.

For avoiding this inconvenience, the disengaging systems are united by connecting devices 40 immediately transmitting the control of one apparatus to the other.

The system connecting the apparatus is suited to the type of life boat; thus, for life boats the central portion of which is free, use can be made 50 of a horizontal transmission, whilst on other boats, the middle portion of the hold or bilge of which is partly inaccessible, use will be made of a vertical transmission.

The horizontal transmission is constituted by 55

two apparatus each comprising a bar 17, longitudinally arranged relatively to the axis of the boat, and the end 18 of which is connected, by a chain or cable 19, to one of the hooks 5 of the device located at the rear of the life boat; this cable 19 is rendered taut by a stretching screw 20. The bar 17 is held by guides 21, secured by lugs 21a on the bottom of the boat.

The bar 17 is provided with a hook 22 pivoted on a pin 22a and the ends 23 of which can enter a metal sheath or sleeve 24 adapted to hold it in closed position; this sleeve is provided with two lugs 25 which when the sleeves slide on the bar 17 will engage with an abutment 26, in order to release the end 23 of the hook 22 for allowing the latter to rock about its pivot pin under the action of the pull exerted by the cable 27, upon release of the beam located at the front of the life boat. This cable is attached to the hook 22 by means of a loop 28.

As above stated, when the beam 1 of the device located at the front part of the life boat has been released from the hooks 5 owing to the flotation of said front part on a wave, this front portion 25 of the boat, by descending in the hollow of said wave, will exert a vertical pull on the cable 27, secured on the beam by a fastening member 28a, which will cause the bar 17 to move in its guides by means of the hook 22 held in the sleeve 30 24. When the lugs 25 of the latter will engage with the abutment 26, it will be held stationary, and the bar 17, continuing to be actuated by cable 27, will cause the end of the hook 22 to come out of the sleeve 24. This hook 22 being no longer held, will pivot through 180° about its pin 22a under the pull of cable 27, thus allowing the disengagement of the loop 28, thus releasing the beam 1.

During the first portion of the displacement of 40 bar 17, the cable 19 exerts on the weight 7 of the hook 5 to which it is secured, a pull compelling it to rock about its pivot pin 6, thus releasing one of the shoulders of the beam of the rear device. The beam being no longer balanced, will 45 rock on its pivot pin 4, releasing the second hook 5. The rear of the life boat being no longer supported by the suspension cable, comes in contact with the water by stretching the cable 27, connecting the beam 1 to the second bar 17 for causing the hook 22 to rock and thus releasing the rear beam.

The life boat being released can move away, and the beams can serve for a second operation.

It is to be noted that the life boat being disengaged from its front device will have a non-dangerous inclination, limited to a few centimeters, the rear device operating nearly simultaneously, owing to the transmission above described.

60 The device indicated is not applicable to launches for instance, as the middle portion of the hold of these boats is very often inaccessible. For these boats, it is therefore necessary to arrange the apparatus vertically at the front and 65 at the rear and perpendicularly to the shoe members.

Each device is constituted by a carriage 29 provided with rollers 30 and with a lug 31. The carriage 29 is adapted for movement vertically in a frame 32, constituted by a channel member provided with a bed plate 33 secured to the bottom of the boat and attached to the deck by its upper part.

70 A track 34, also constituted by a channel member, is secured on the bed plate 33, opposite the

frame 32 and parallel to the latter; this track 34 is adapted to hold the tripping device carried by carriage 29 in such a position that the cable 27 of the beam 1 remains attached by its loop on a finger 35, arranged in an opening 36 formed in a lever 37 pivoted about a pin 38 carried by a carriage 29.

The end of the lever 37 terminates in a fork member carrying a roller 39, which will roll on track 34 upon disengagement of the device.

10 The carriage is connected, by a cable 19, to one of the hooks of the opposite device. This cable 19 is attached to the lower part of the carriage 29 and is guided by pulleys 40. Throughout the length of the boat, this cable is guided in a tube secured on the framing of the boat.

15 The operation of this device is similar to that previously described.

When the front beam *a* for instance (Fig. 7) 20 is freed from the hooks, under the action of the waves the mass of the boat exerts a pull on the stationary cable 27, thus compelling the carriage 29 to move in its frame 32 in the direction indicated by the arrow *x*. The roller 39, arranged at the end of the lever 37, also rolls on its track 25 34 and when it reaches the extreme portion (Fig. 7), it slips off and the lever 37 rocks about its pivot, placing the finger 35 in an approximately vertical position. The loop 28 which was placed 30 on this finger leaves it, thus completely releasing the front portion of the boat from its suspension device.

As soon as the carriage 29 begins to move in its frame, the cable 19, attached to its lower part 35 (Fig. 7) acts on the hook 5 of the device *b*, located at the rear, for disengaging it from the shoulder 2 and obtaining, by unbalancing of the beam 1, the automatic disengagement of the second hook. The boat being released from its suspension apparatus, floats, and the carriages 29 40 fall down their frames (Fig. 8).

The systems described above allow to very easily launch a boat and its passengers, whilst eliminating the difficult operations of disengaging the suspension cables in rough weather.

45 They allow:

The automatic disengagement of any heavy weight as soon as the vertical pull of the suspension members ceases to act on the same.

50 The disengagement, also automatic, of a weight hung by both its ends, as soon as one of these ends disengages, whilst preserving in its descent a position approximating that it had during advance.

55 The disengagement at will of a weight at a small height above the point where it is to drop by the disengagement of one of the members of the suspension apparatus.

This apparatus ensures safety after each automatic operation of the transmission, whilst preserving intact the main part of the plant.

60 It is to be understood that, according to circumstances, use can be made of one or two suspension devices and that their shape can vary as well as their system of attachment.

65 I claim:—

70 1. A suspending and releasing device for heavy loads such as lifeboats, comprising a suspending cable, a substantially horizontal beam pivotally secured intermediate its ends to the suspending cable, a pair of supporting arms pivotally mounted on the lifeboat, supporting members pivotally mounted on said arms and adapted to engage under the action of the load the ends of 75 said beam, and counterweights associated with

said supporting members and adapted to disengage the latter from said beam when the load ceases.

2. A suspending and releasing device as claimed 5 in claim 1, comprising manually operated means for disengaging at least one of the supporting members from the beam.

3. A suspending and releasing device as claimed in claim 1, comprising a shoe, a horizontal axis 10 pivotally securing said shoe to the lifeboat, horizontal pivot pins mounted on said shoe at right angles with respect to said axis, said supporting arms being mounted on said pivot pins.

4. A suspending and releasing apparatus for 15 heavy loads comprising two devices as claimed in claim 1, traction members connecting the beam of each device to one supporting member of the other device and releasable coupling means mounted in said traction members.

5. A suspending and releasing apparatus for heavy loads such as lifeboats, comprising two devices as claimed in claim 1, a traction member connected to a supporting member of one device, a coupling member slidably mounted in the lifeboat and connected to said traction member, a hook pivotally mounted on said coupling member, a second traction member attached to the beam of the other device, a loop formed at the end of said second traction member and engaging said hook, and a guide member mounted in the lifeboat and maintaining said hook in a loop-retaining position when said coupling member is in its normal position, but liberating said hook so as to liberate the loop when said coupling member 15 is displaced from its normal position.
